UNITED STATES PATENT OFFICE

108,235

DESIGN FOR A DISPLAY STAND

Raymond A. Hennings, New Orleans, La., assignor of one-half to Alphonse G. Tennis, New Orleans, La.

Application September 17, 1937, Serial No. 71,661

Term of patent 7 years

To all whom it may concern:

Be it known that I, Raymond A. Hennings, a citizen of the United States, residing at New Orleans, in the parish of Orleans and State of Louisiana, have invented a new, original, and ornamental Design for Display Stands, of which the following is a specification, reference being had to the accompanying drawings, forming part thereof.

I claim:

The ornamental design for a display stand, as shown.

RAYMOND A. HENNINGS.
